The ornamental design for an automatic teller machine, as shown and described.

DESCRIPTION

FIG. 1 is a top, front, and right side perspective view of an automatic teller machine showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a right side view thereof with a section of the outer housing cut away to show the bottom touch display panel in an alternate position.

The even dashed broken lines represent portions of the automated teller machine that form no part of the claimed design. The dash-dot broken lines show a cut-away section in FIG. 8.
